UNITED STATES PATENT OFFICE.

REGINALD V. WILLIAMS, OF BUFFALO, NEW YORK.

DENTAL CLASP.

1,412,224.

Specification of Letters Patent. Patented Apr. 11, 1922.

Application filed November 23, 1920. Serial No. 426,049.

To all whom it may concern:

Be it known that I, REGINALD V. WILLIAMS, a citizen of the United States, residing at Buffalo, in the county of Erie and State of New York, have invented new and useful Improvements in Dental Clasps, of which the following is a specification.

This invention relates to the clasps employed for removably securing dental plates or bridgework to natural teeth.

Heretofore such clasps have been cast in one piece of a suitable alloy, or made of several pieces secured together by hand-soldering. Cast clasps are undesirable, because their parts cannot be bent or reversed to form a right or left clasp without cracking or breaking them. Soldered, multi-piece clasps require considerable time to make and adjust them and also incur waste of material. The spurs and occlusal rests of such clasps are also liable to break off, and the seams or joints form projecting edges or shoulders on which foreign matter lodges, rendering the clasps unsanitary. The soldering operation, moreover, draws the temper from the metal to a greater or less extent, impairing the resilience of the clasp and weakening its grip on the tooth.

The chief object of my invention is the provision of a dental clasp which is sufficiently stiff and resilient to reliably retain its shape and grip and yet strong and flexible enough to permit bending or refitting of the clasp, if required, without liability of breaking.

Further objects are to provide a neat, ready-made clasp which requires no soldering and therefore effects a material saving in time and material, which is smooth, seam-less and sanitary and whose parts can be readily and safely reversed to produce either a right or a left clasp, as desired.

In the accompanying drawings: Figure 1 is a perspective view of a pair of dental plates provided with the improved clasps. Figure 2 is a vertical longitudinal section of a fragment of one of the plates, on an enlarged scale. Figure 3 is an exaggerated perspective view of the clasp. Figure 4 is an inverted perspective view thereof. Figure 5 is a plan view of the blank from which the clasp is formed.

Similar characters of reference indicate corresponding parts throughout the several views.

The clasp comprises the customary band 10 which embraces the tooth, and the offset spur 11 which is embedded in the dental plate or soldered to the bridgework. For molars and bicuspids, the clasp has the usual lug or occlusal rest 12, which is sometimes not used for cuspids. To more securely anchor the spur in place, it is preferably provided with transverse ribs or corrugations 13 and it may also be stiffened by a longitudinal rib 14.

The entire clasp, including the occlusal rest, if used, is formed in a single piece from a flat blank of sheet metal, of the shape shown in Fig. 5, or approximately so. This blank comprises a slightly bowed bar 10^a adapted to form the curved band of the clasp; a short tongue 12^a projecting centrally from the concave edge of said bar and adapted to form the rest 12, and a relatively long tongue 11^a projecting in the opposite direction from the convex edge of said bar and offset with reference to said central tongue, this long tongue forming the spur of the completed clasp. This blank is stamped from any suitable metal or alloy, preferably an alloy of gold and platinum having the requisite stiffness and elasticity to enable the clasp to retain its form and tightly grip a tooth, while possessing sufficient strength and flexibility to permit the clasp to be repeatedly bent without breaking any of its parts, in refitting or readjusting the clasp.

To make a sectional or multi-piece clasp by hand requires about half an hour. By the use of this improved integral ready-made clasp, the dentist saves not only that important item of time, but also a considerable amount of material, because there is no waste. Such unsoldered, one-piece clasps are further economical in that they require less platinum. When gold is soldered to gold, it is necessary to use a larger percentage of platinum or high-content platinum alloy to withstand the high degree of heat required to solder the spur and the occlusal rest to the band.

Cast clasps, moreover, entail loss of gold, because they have to be ground to fit them

to the teeth, the resulting gold dust floating in the air and finally dropping on the floor, thus largely going to waste. No such loss is incurred in the manufacture and use of the 5 improved clasp, because it requires no grinding but can be accurately fitted or adjusted by simply bending its parts.

Unlike a cast or soldered multipiece clasp, the band can be reversely curved or bent in 10 either direction and the spur and the rest bent or reversed accordingly, to make either a right or a left clasp without danger of breakage, thus requiring only one set of dies for stamping both kinds.

15 As the parts of the clasp are not subjected to a soldering or heating operation of any kind, they retain their original temper and resilience.

While combining the necessary resilience 20 and strength, the clasp is smooth and seamless, rendering it comfortable to the wearer, as well as sanitary since it presents no raised edges or lodging places for particles of food.

The clasp is sold in flat or blank form and made in several sizes to fit different teeth. 25

In the drawings, the band is shown flat-sided, but it may be of round, half-round, oval or any other suitable cross section.

I claim as my invention:

1. A one-piece dental clasp having an 30 occlusal rest and stamped from a flat sheet metal blank comprising a bowed bar and a comparatively short tongue projecting from the concave edge of said bar.

2. A one-piece dental clasp having a spur 35 and stamped from a flat sheet metal blank comprising a bowed bar and a tongue extending from the convex edge of said bar.

3. A one-piece dental clasp having a spur 40 and an occlusal rest and stamped from a flat sheet metal blank comprising a bowed bar, a short tongue projecting centrally from the concave edge of said bar and a long tongue projecting from the opposite convex edge of the bar and offset from said short tongue. 45

REGINALD V. WILLIAMS.
